J. J. DILKS

REENFORCEMENT FOR MOVING PICTURE FILMS

Filed March 20, 1923

Fig. 2.

INVENTOR

JAMES J. DILKS,

By HIS ATTORNEY

Kreider, King & Taubbank

UNITED STATES PATENT OFFICE.

JAMES J. DILKS, OF PHILADELPHIA, PENNSYLVANIA.

REENFORCEMENT FOR MOVING-PICTURE FILMS.

Application filed March 20, 1923. Serial No. 626,292.

To all whom it may concern:

Be it known that I, JAMES J. DILKS, a citizen of the United States, residing at Philadelphia, county of Philadelphia, State of Pennsylvania, have invented a new and useful Reenforcement for Moving-Picture Films, of which the following is a specification.

My present invention relates to a reinforcing strip to motion picture films and consists of a novel reinforcing device which can be expeditiously and effectively applied to the apertured edges of films of the character referred to.

It further consists of a novel reinforced perforated film to be hereinafter referred to having the reinforcing strip applied to the perforated zone, said strip having means which pass through perforations in the film but which are free from contact with the edges of said perforations, in combination with means for longitudinally reinforcing said film.

It further consists of other novel features of construction and advantage all as will be hereinafter fully set forth.

For the purpose of illustrating my invention, I have shown in the accompanying drawing an embodiment thereof which is at present preferred by me, since this embodiment will be found in practice to give satisfactory and reliable results. It is, however, to be understood that the various instrumentalities of which my invention consists can be variously arranged and organized and that my invention is not limited to the precise arrangement and organization of these instrumentalities as herein shown and described.

The object of my invention is to provide an effective reenforcement for the perforations and edges of motion picture film, an object which I attain in the manner herein-after set forth, reference being had to the accompanying drawing, in which—

Fig. 1 is a face view of a section of motion picture film having its perforations and edges reinforced in a manner in accordance with my invention,

Fig. 2 is a transverse sectional view, on a larger scale, on the line 2—2, Fig. 1, and

Fig. 3 is a longitudinal sectional view, on the same scale as Fig. 2, on the line 3—3, Fig. 1.

Referring to the drawing, there is illustrated a strip 1 of film provided, adjacent

each edge, with the customary longitudinal row of perforations 4 for engagement with the toothed feed-wheels of camera or projector. The film is of such a delicate nature that it is desirable to reinforce it in the regions of the perforations in order that it may more readily withstand the strains and stresses to which it is subjected, and this I accomplish by applying to the face of the film, in alignment with each longitudinal row of perforations 4, a longitudinal strip of suitable flexible material 5, adapted to cover the zone of perforation and provided, coincidently with each perforation 4, with a pair of wings 6 which project through the perforation and are oppositely bent back and clamped against the opposite face of the film, as is best shown in Fig. 3. With this construction, when the film is fed through camera or projector, the toothed feed-wheels engage with the wings 6 of the reinforcing strip 5 and do not come into contact with the edges of the perforations in the film. To render the reinforcement of especial value, the wings 6, in their passage through a perforation 4, are provided with a central alignment in respect thereto as a result of which they are free from contact with the edges thereof, as is also best shown in Fig. 3. By this means, the entire grip of the reinforcing strip 5 is upon the upper and under faces of the film and, at no time, is any strain placed upon the edges of the perforations 4.

In order to reinforce the edges of the strip of film 1, each reinforcing strip 5 is of such width that its outer edge may be turned down over the outer edge of the film and bent back against the opposite face thereof, so as to form a lip 7, which terminates at a point between the sprocket holes and the longitudinal edges of the film whereby the bottom space 8 of the film between the edge of said lip 7, and the line of sprocket holes is not covered with metal, so that its resiliency is unimpaired. This construction, which is best shown in Fig. 2, effectively eliminates any tendency which the film may possess to crack or split inwardly from its edges, and it will be further apparent that since the lip 7 is in close frictional contact only with the underside of the film, a more effective reenforcement is provided than in prior devices where the entire bottom reenforcements extend from the longitudinal edges clear to or across the sprocket holes and are

immovably clinched or cemented to the under side of the film.

If desired, only one wing 6 need be provided on the reinforcing strip 5 to cooperate with each perforation 4 in the film 1, this wing being the one at the forward edge of the perforation as the film is being fed through camera or projector. Such a modification of my invention, as well as others equally simple, are obvious, and require no especial illustration, it being understood that I do not limit myself to the exact construction shown in the drawing.

It will now be apparent that I have devised a novel and useful reenforcement for moving picture films which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages.

I claim:

1. The combination with a film having sprocket holes along its opposite side edge portions, of longitudinally extending perforated reinforcing strips arranged along the opposite side edges of said film and having holes aligning with said sprocket holes, and integral clinching devices on said strips for securing the latter with respect to the walls of said sprocket holes, the outer edges of said reinforcing strips being extended

around the contiguous outer edge of the film and being bent under the latter and in frictional contact therewith to form longitudinally extending lips to protect the side edges of said film, the edges of the underfolded lip portions of said reinforcing strips terminating between the sprocket holes and the longitudinal edges of said film.

2. The combination with a film strip having sprocket holes along its opposite side edge portions, of longitudinally extending perforated reinforcing strips arranged along the opposite side edge portions and having holes aligning with said sprocket holes, each of said reinforcing strips having a pair of integral wings adjacent to each of its holes and passing through the hole of the film strip with which the hole of the reinforcing strip aligns, said wings extending transversely of the film strip and clinched on the opposite side surface of the film, the outer edge of each of said reinforcing strips extending around the contiguous outer edge of the film strip and being bent under the latter to form longitudinally extending lips to protect a side edge of the film strip and prevent said wings from shifting transversely in one direction and tearing the film strip; the edges of the underfolded lip portions of said reinforcing strips terminating between the sprocket holes and the longitudinal edges of the film, and being in frictional engagement with said longitudinal edges.

JAMES J. DILKS.
